United States Patent Office.

H. B. SMITH, OF ESSEX, CONNECTICUT.

Letters Patent No. 78,145, dated May 19, 1868.

IMPROVEMENT IN FANS.

The Schedule referred to in these Letters Patent and making part of the same.

TO ALL WHOM IT MAY CONCERN:

Be it known that I, H. B. SMITH, of Essex, in the county of Middlesex, and State of Connecticut, have invented a new and improved Pocket-Fan; and I do hereby declare that the following is a full, clear, and exact description thereof, which will enable those skilled in the art to make and use the same, reference being had to the accompanying drawing, forming part of this specification, in which—

Figure 1 represents a face view of my improved fan, showing it expanded.

Figure 2 is a face view of the same, showing it folded together.

Similar letters of reference indicate corresponding parts.

This invention relates to a new ladies' fan, which is so arranged that its handle can be folded out of the way when the fan is folded together; thereby the handle will be protected, and will not be so liable to break off. In the fans now made the handle projects from the fan even when the same is folded together, and it does thereby not only cause the fan to occupy much space, but is also liable to break off.

I am aware that, with a view of avoiding this inconvenience, some handles have been pivoted to the same pin by which the wings of the fan are held together, but by such an arrangement only a semicircular fan can be provided.

My invention consists in pivoting the handle to the outer end of one of the fan-wings, whereby a full, complete circular fan can be arranged.

A, in the drawing, represents the wings of a fan, said wings being of suitable shape and design, and made of suitable material.

The wings are all connected with each other by means of a pin, B, and may also, by means of a cord, α , or its equivalent, be held together at their outer ends.

To the outer ends of the extreme wings, A', are pivoted, by means of pins b , the handles C-C, as is clearly shown in fig. 1.

These handles are, when the fan is folded together as in fig. 2, on the outside of the fan, and can be turned so as to rest on the wings to which they are attached, as shown.

From fig. 2 it will appear that this fan, when folded together, will occupy but a small space, is not liable to break, and can be conveniently carried in the pocket.

I claim as new, and desire to secure by Letters Patent—

As a new article of manufacture, a fan, whose handles C are pivoted to the outer ends of the extreme wings of the same, substantially as described, for the purpose of allowing them to be folded out of the way, as set forth.

H. B. SMITH.
